UNITED STATES PATENT OFFICE.

CLARK W. DIMOND, OF MINNEAPOLIS, MINNESOTA.

MANIFOLD-HEAT RETAINER.

Application filed January 16, 1925. Serial No. 2,916.

This invention relates to improvements in means for heating the fuel charges of internal combustion engines.

The primary object of this invention is the provision of means for utilizing the heat from the exhaust manifold of an internal combustion engine, in order to heat the fuel charge passing through the intake manifold to the engine.

10 A further and important object of this invention is the provision of a heater structure of the above mentioned character which includes means for utilizing the heat radiating from the exhaust manifold of an internal combustion engine, for the purpose of heating fuel charges in the carburetor and intake manifold of the internal combustion engine.

20 A further object of this invention is the provision of a heater structure of the above mentioned character which includes a section adapted to house the exhaust and intake manifold, and a section adapted for detachable connection with the first mentioned section for housing the carburetor whereby to utilize the heat from the exhaust manifold for the purpose of heating the fuel passing through the carburetor.

30 Other objects and advantages of this invention will be apparent during the course of the following detailed description.

In the accompanying drawing, forming a part of this specification, and wherein similar reference characters designate corresponding parts throughout the several views,

35 Figure 1 is a fragmentary side elevation of an internal combustion engine, showing the improved heater structure as cooperating with the intake and exhaust manifold on the carburetor of the internal combustion engine.

40 Figure 2 is an end elevation, partly in section, of the improved heater structure, showing the same looking toward the front of the internal combustion engine, in cooperating position with the manifold and carburetor details of the internal combustion engine.

45 Figure 3 is a cross sectional view of the heater unit alone, taken substantially on the line 3-3 of Figure 1.

50 Figure 4 is an enlarged fragmentary sectional view of the heater unit alone, taken substantially on the line 4-4 of Figure 2, and

55 Figure 5 is a cross sectional view of the

heater unit alone, taken substantially on the line 5-5 of Figure 1.

In the drawing, wherein for the purpose of illustration is shown only the preferred embodiment of the invention the letter A may generally designate the internal combustion engine and its details, with the improved heater structure B.

60 In the internal combustion engine A, it is preferred that the same include the cylinder block 10, having the exhaust manifold 11 and the intake manifold 12 provided at the same side thereof. The exhaust and intake manifolds 11 and 12 are, of course, of any approved type, and in the preferred instance they are maintained in assembled relation by means of clamp structures 14, which assist in holding the heater structure B in position, as will be subsequently described. The intake manifold 12 includes the downwardly extending tubular portion 15, which has connection with the carburetor 16 of any approved type. A conventional fan structure 17 may be provided forwardly of the internal combustion engine A, for cooling purposes, in accordance with any approved construction. It is well known that the draft of air passes over the exhaust, intake, and carburetor details of the internal combustion engine, cooling the same, so that the vaporized fuel is permitted to pass into the internal combustion engine cylinders without any preheating influence acting thereon. The heater structure B is provided in order to benefit by the heat radiated from the exhaust manifold 11, for the purpose of preheating fuel in the intake manifold and in the carburetor, to render the same more volatile.

65 Referring to the structure B, the same includes the section 20 adapted to house the intake and exhaust manifolds, and the section 21 detachable with respect to the section 20 and adapted for housing the carburetor 16.

70 The sections 20 and 21 are preferably constructed of copper, aluminum, or some analogous metal material, and they are preferably bent to their respective shapes without riveting, and so that they can be readily detached with respect to each other and with respect to the internal combustion engine.

75 The section 20 preferably includes the main body wall 25, which upwardly thereof is provided with the laterally extending arcuated top wall 26 adapted to extend over

the top of the exhaust manifold 11 and at its edge 28 adapted to rest on the top of the cylinder head of the internal combustion engine. The wall 26 is not of uniform cross section throughout its length, and at the front thereof the same is not arcuated in cross section, but is preferably flat, as is illustrated in the sectional view of Figure 5, so that the edge 29 engages against the side of the cylinder block of the engine. The section 20 furthermore includes a front wall 30, of course, integral with the top and main walls above mentioned, and extending from the top wall 26 thence downwardly on an arcuation; the same with respect to the internal combustion engine sloping downwardly and rearwardly with a stream-like effect, for the purpose of enclosing the intake and exhaust manifolds to ward off the air stream therefrom. The front wall 30 merges into the bottom wall 31 provided for disposition below the portion 15 of the intake immediately adjacent the carburetor, for the purpose of shielding the same. No rear walls are provided for the section 20, and it is to be noted that the compartment 33 provided by the section 20 receives the intake and exhaust manifolds of the internal combustion engine for the purpose of shielding them and providing a compartment within which the heat from the exhaust manifold may pass about the intake manifold and be conveyed to the carburetor and to the section 21, as will be subsequently mentioned.

The section 21, which is solely for the purpose of housing the carburetor 16 is adapted to be supported by the section 20. This section 21 includes the side wall 40; bottom wall 41; rear concavo-convex wall 42; and a short wall 43 adapted to be positioned between the carburetor and the internal combustion engine and in substantially parallelism with the wall 40. The bottom wall 41 extends for a short distance upwardly at its forward end, and is provided with an attaching flange 44 adapted to be positioned below the bottom wall 31 of the section 20, for attachment thereto. This attachment 45 consists of a plurality of bolts with wing nuts therefor; three of the bolts 45 being preferably provided for detachable connection of the flange 44 to the wall 31; the wing nuts 46 being lowermost and exposed where 50 they are readily accessible to any one desiring to detach the sections 20 and 21. It is preferred that the side wall 40 of the housing 21 having an attaching ear 48 laterally extending therefrom, which is adapted to be connected to the front wall 25 of the section 20 by means of a bolt 50 and wing nut 51, with the wing nut 51 outermost to permit 55 of detachment.

Referring more particularly to the operation of the invention, it is to be noted

from Figure 2 of the drawing, that the section 20 when placed in assembled relation against the internal combustion engine is clamped thereto by means of the clamping structures 14 conventionally used with the engine A. For this purpose a plurality of openings 53 are provided in the wall 25 to receive the bolts of the clamping structures 14 thereto. The section 21 assembled in this relation to the internal combustion engine provides a compartment 33 which is enclosed at the front except for the forward opening 55 between the lateral edge of the front wall 30 and the engine block, for the purpose of permitting the air from the fan 17 to pass along the cylinder block at a point below the intake manifold 12 to permit the cooling effect of the air upon the cylinder casing, without interfering with the downward passage of heat from the exhaust manifold to the carburetor casing 21. The heat passes downwardly through the compartment 33, and into the carburetor casing 21, since the sections 20 and 21 are communicating, as is illustrated in Figure 4 of the drawing, and as the housing 21 is in spaced relation to the carburetor, the heat may pass readily thereabout for preheating the fuel therein. No top wall is provided for the casing 21, so that the heat after passing about the carburetor may escape. Suitable openings are provided in the bottom wall 41 and the rear wall 42 of the housing 21 for receiving the drain cock and fuel line details 60 and 61 respectively of the carburetor. Since no top wall is provided for the housing or section 21, the carburetor operating details are at all times accessible.

From the foregoing description of this invention it is apparent that a heater unit for rendering the fuel of internal combustion engines more volatile has been provided, which is relatively simple in character, and one which can be easily attached. It involves a correct principle in that it does not interfere with the cooling efficiency of the fan, and yet permits proper direction of heat to the carburetor and to the intake manifold. The carburetor section 21 need only be employed in extremely cold weather, and in summer this section 21 may be readily detached, and the section 20 utilized by itself, since it has been found that the section 20 is then only necessary to preheat the fuel to the proper degree. It is to be noted that the carburetor is especially protected forwardly and below the same, and when the motor is not running the heat of the casing 21 will warm the fuel in the carburetor for a considerable length of time, and at all events will prevent cold air drafts from passing about the carburetor.

Various changes in the shape, size, and arrangement of parts may be made to the form of the invention herein shown and described,

without departing from the spirit of the invention or the scope of the claims.

I claim:

1. As an article of manufacture a heater structure for internal combustion engines including a section providing a main side wall, a top wall, a front wall, and a bottom wall, said section being open at the rear, a second section including a bottom wall, a side wall, a rear wall, and being open upwardly thereof, and means detachably connecting said sections so that the compartments therein are in communication at the lower portion of the first mentioned section.
2. In combination with an internal combustion engine and including a cylinder block, intake and exhaust manifolds, and a carburetor, a housing for enclosing the intake and exhaust manifolds and including a single side wall, a top wall arcuating over 20 the exhaust manifold, and a forward wall arcuating in stream line manner from the top wall downwardly along the cylinder block in rearwardly sloping relation to protect the intake and exhaust manifolds from 25 air currents from forwardly of the internal combustion engine, a bottom wall for said casing adjacent said carburetor, and a carburetor casing including an outer side wall, an arcuate rear wall, a short inner side wall, 30 a bottom, and being open at the top thereof, and means detachably connecting the carburetor casing with said first mentioned heater casing to permit flow of heat from the first mentioned housing into the carburetor casing between the same and said carburetor.

CLARK W. DIMOND.
